UNITED STATES PATENT OFFICE.

GEORGE S. EMERICK, OF PHILADELPHIA, PENNSYLVANIA.

AIR-SEPARATOR.

1,263,394.

Specification of Letters Patent. Patented Apr. 23, 1918.

Application filed January 27, 1917. Serial No. 144,831.

To all whom it may concern:

Be it known that I, GEORGE S. EMERICK, a citizen of the United States, residing at Philadelphia, in the county of Philadelphia and State of Pennsylvania, have invented 5 certain new and useful Improvements in Air-Separators, of which the following is a specification.

My invention relates to improvements in 10 air separators for separating the finer particles from the larger particles of previously ground or comminuted material and wherein are employed a casing inclosing a separating chamber, an upper receptacle supported within the chamber in spaced relation to the casing and having an open top and an open bottom, a lower receptacle supported within the chamber below the upper receptacle and having an 15 upper open end spaced from the lower end of the upper receptacle, means to feed the previously ground material to the upper receptacle so that it will descend therethrough, and means to cause air to circulate 20 through and around said upper receptacle and through the space between said receptacles, whereby as the ground material descends through the upper receptacle and passes the open space between the receptacles, the air entering said space from 25 the exterior of the receptacles and passing up through the upper receptacles will carry with it the finer particles of the ground material and discharge it outwardly from the 30 upper end of the upper receptacle and into the casing surrounding the same, while the larger particles of the ground material descend into the lower receptacle.

The object of my invention is to improve 35 machines of this class by the provision of a novel, simple and efficient means to regulate the volume of air passing through the space between said receptacles without raising or lowering either of the receptacles; and, with this object in view, my invention consists in the novel construction and combinations of parts hereinafter fully described and claimed.

In the accompanying drawings, illustrating my invention:

Figure 1 is a vertical section through a separating machine, embodying my invention.

Fig. 2 is a plan view thereof.

Fig. 3 is a sectional detail, showing a portion of the means for controlling the vol-

ume of air passing through the space between the receptacles.

Referring to the drawings, 2 designates the outer casing of the machine which incloses the separating chamber 4. The lower portion of the casing 2 is made tapering and is provided with a discharge opening 5 in the bottom thereof for the discharge of the finer particles of the separated material.

Within the upper portion of the chamber 4 and spaced from the casing 2 is the upper receptacle 6 which has an open top and an open bottom and which is supported by bolts 7 depending from the top 8 of the casing 2 and connected to brackets 9 which project outwardly from the receptacle 6.

Extending vertically through the top 8 of the casing 2, centrally thereof, is a feed pipe 10 through which the material to be separated is fed to the machine. This pipe 10 extends down into the receptacle 6 through a hollow, vertical shaft 11 which is mounted to turn in a suitable bearing 12 on the top 8 of the casing 2. The pipe 10 is supported by a bracket 13 suitably supported above the bearing 12. The shaft 11 is provided with a bevel gear wheel 14 in mesh with a similar wheel 15 on a horizontal shaft 16 which turns in bearings 17 on the top 8 of the casing 2. The shaft 16 is provided with a pulley 18 by means of which it and the shaft 16 may be rotated. The bottom of the shaft 11 carries a pair of spaced, round disks 19, the upper one of which has a central opening therein through which the lower end of the feed pipe 10 extends. The material to be separated is discharged from the bottom of the pipe 10 upon the lower plate 19, and, during the rotation of the shaft 16, the material is discharged by centrifugal force from the edge of the lower plate 19 into the receptacle 6.

Secured to the shaft 11 is a collar 20 provided with outwardly projecting arms 21 which carry fan blades 22 within the chamber 4 and above a horizontal plate or flange 23 which extends outwardly from the top of the receptacle 6, whereby, when the shaft 11 is rotated, air is caused to circulate through and around the receptacle 6, as will be hereinafter explained.

The central portion of the receptacle 6 is expanded and the feed plates 19 extend into the expanded portion of the receptacle, and the diameter of the plates 19 is equal to or

greater than the diameter of the open top and the diameter of the open bottom of the receptacle 6, so that all air passing up through the receptacle 6 will be caused to 5 pass through the curtain of material falling from the feed plates 19. The portion of the receptacle 6, below the feed plates 19, is tapered inwardly and downwardly to receive the ground material from the feed 10 plates 19 and cause it to descend by gravity and to be thereby discharged from the open bottom of the receptacle 6.

The lower receptacle 24 is located below the upper receptacle 6 and is spaced therefrom and has an upper open end of a diameter which is equal to or greater than the diameter of the open bottom of the upper receptacle 6, so that the material falling from the upper receptacle 6 will be received 15 within the lower receptacle 24. The lower receptacle 24 is supported by spaced arms or brackets 25 which extend vertically between the receptacles 6 and 24 and are secured thereto. The lower receptacle 24 is made 20 tapering or funnel shaped and its lower end terminates in a downwardly extending pipe 26 which extends outwardly through the casing 2 for the discharge of the larger particles of the separated material.

30 Surrounding the space 27 between the two receptacles 6 and 24 is an inner casing 28 which is spaced from the outer casing 2 and from the receptacles 6 and 24. The upper end of the casing 28 is closed and connected 35 to the upper receptacle 6 and supported thereby by means of brackets 29. The lower end of the casing 28 is open and it extends to a position at or below the line of the top of the lower receptacle 24.

40 The fan blades 22 are set to cause air to circulate within the chamber 4 up through the inner casing 28, through the space 27, up through the upper receptacle 6 and down through the chamber 4 outside of the receptacle 6 and the inner casing 28, during the rotation of the shaft 11.

Within the inner casing 28 and surrounding the arms 25 is a horizontally-disposed, annular valve plate 30 which extends from 50 the wall of the casing to the space 27 and is adapted to control the volume of air passing through the space 27, during the operation of the fan 22. The valve plate 30 is supported by suitable cables 31 having their 55 lower ends connected thereto and extending up through openings in the top of the casing 28 and over and under guiding rollers 32 and 33, supported on brackets on the receptacle 6 and casing 2, respectively. The upper ends of the cables 31 are connected to the lower ends of vertically movable bars 34 which extend through openings in the top 60 of the casing 2 and have suitable handles on the upper ends thereof, by means of 65 which the bars 34 and therewith the valve

plate 30 may be raised and lowered. The bars 34 are provided with perforations 35 which extend horizontally therethrough to receive pins 36 which are adapted to engage the top 8 of the casing 2 and support the 70 bars 34 and valve plate 30 in different positions of adjustment.

During the circulation of the air within the chamber 4, by the operation of the fan blades 22, the valve plate 30 prevents the air 75 passing up through the casing 28 from passing above the valve plate 30 until after the air passes through the space 27 between the receptacles 6 and 24. It will, therefore, be understood that the volume of air passing 80 through the space 27 may be nicely regulated by adjusting the valve plate 30 vertically to different positions within the casing 28.

I preferably employ four bars 34 and their connections to adjust and support the valve 85 plate 30, and I space the bars 34, as shown in Fig. 2, so that two men may raise or lower the valve plate 30 by taking hold of the handles of two bars 34 on opposite sides of the machine; and so that thereafter the 90 plate 30 may be prevented from tilting by adjusting the two remaining bars 34.

When it is desired to regulate the volume of air passing down between the outer and inner casings 2 and 28, respectively, I provide a vertically movable damper 37 which surrounds the inner casing 28 and which is adapted to be raised and lowered by raising and lowering bars 38 which are connected to the damper 37 by cables 39 passing around suitable guiding pulleys 40. These bars 38 are constructed and adjusted similarly to the bars 34.

The operation of the machine is as follows:

Power is applied to the pulley 18 to rotate the shaft 16 and therewith the fans 22 and feed plates 19. This operation causes a circulation of air within the chamber 4 and through the inner casing 28 and the upper receptacle 6 as previously described. The material to be separated is fed into the machine through the feed pipe 10, and is deposited upon the lower plate 19 and passes by centrifugal action out through the space 115 between the plates 19 and is discharged from the outer edges thereof into the expanded portion of the upper receptacle 6 and into the air passing upwardly therethrough and around the outer edges of the feed plates 19. 120 The material falls through the upper receptacle 6 and from the open bottom thereof into the open top of the lower receptacle 24; and, during this operation, the finer and lighter particles of the material are carried upwardly by the ascending air and discharged outwardly over the top of the upper receptacle 6 while the larger and heavier particles of the material descend and pass 125 through the lower receptacle 24 and out 130

through the discharge pipe 26 leading from the bottom thereof. The finer and lighter particles of the material, after being discharged from the top of the upper receptacle 6, descend through the chamber 4 exteriorly of the receptacles 6 and 24 and inner casing 28 and are discharged from the machine through the opening 5 in the bottom of the casing 2.

10. It will be observed that the space 27 between the receptacles 6 and 24 and through which the material to be separated falls in passing from the upper to the lower receptacle remains constant while the valve plate 15 30 may be adjusted to vary the volume of air passing into the space 27, thereby enabling me to preserve the distance of travel of the material through the separating zone, and, at the same time, to vary the volume of air 20 passing through the space 27 between the receptacles, resulting in a more efficient operation.

I claim:

1. In an air separator, the combination of 25 an outer casing inclosing a chamber, an upper receptacle supported within the chamber in spaced relation to said casing and having an open top and an open bottom, a lower receptacle supported within the chamber 30 below the upper receptacle and in spaced relation to said casing and having its upper end spaced from the lower end of the upper receptacle, an inner casing connected to the upper receptacle and extending downwardly therefrom and surrounding the space 35 between said receptacles and opening into said chamber exteriorly of the receptacles, means to cause air to circulate between said receptacles and through and around said upper receptacle and said inner casing, an adjustable valve within said inner casing for 40 varying the space between said receptacles through which air is permitted to circulate, and means for feeding the material to be 45 separated to said upper receptacle.

2. In an air separator, the combination of an outer casing inclosing a chamber, an upper receptacle supported within the chamber in spaced relation to said casing and having 50 an open top and an open bottom, a lower receptacle supported within the chamber below the upper receptacle and in spaced relation to said casing and having its upper end spaced from the lower end of the upper receptacle, an inner casing connected to the upper receptacle and extending downwardly therefrom and having an open bottom and surrounding the space between said receptacles, means to cause air to circulate between 55 said receptacles and through and around said upper receptacle and said inner casing, a vertically adjustable valve plate extending horizontally through said inner casing for varying the space between said receptacles through which the air is permitted to circ-

ulate, and means for feeding the material to be separated to said upper receptacle.

3. In an air separator, the combination of an outer casing inclosing a chamber, an upper receptacle supported within the chamber 70 in spaced relation to said casing and having an open top and an open bottom, a lower receptacle supported within the chamber below the upper receptacle and in spaced relation to said casing and having its upper end 75 spaced from the lower end of the upper receptacle, an inner casing connected to the upper receptacle and extending downwardly therefrom and having an open bottom and surrounding the space between said receptacles, means to cause air to circulate between said receptacles and through and around said upper receptacle and said inner casing, a vertically adjustable valve plate 80 extending horizontally through said inner casing for varying the space between said receptacles through which the air is permitted to circulate, and means operative to adjust said valve and to support it in different positions of adjustment, and means for 85 feeding the material to be separated to said upper receptacle.

4. In an air separator, the combination of an outer casing inclosing a chamber, an upper receptacle supported within the chamber 95 in spaced relation to said casing and having an open top and an open bottom, a lower receptacle supported within the chamber below the upper receptacle and in spaced relation to said casing and having its upper 100 end spaced from the lower end of the upper receptacle, an inner casing connected to the upper receptacle and extending downwardly therefrom and having an open bottom and surrounding the space between said receptacles, means to cause air to circulate between said receptacles and through and around said upper receptacle and said inner 105 casing, a vertically adjustable valve plate extending horizontally through said inner casing for varying the space between said receptacles through which the air is permitted to circulate, vertically movable bars extending through the top of the outer casing, cables connecting said bars and said valve plate, whereby when said bars are raised and lowered said valve plate will be raised and lowered, and means to support said bars in different positions of adjustment.

5. In an air separator, the combination of 120 a casing inclosing a chamber, an upper receptacle supported within the chamber in spaced relation to said casing and having an open top and an open bottom, a lower receptacle supported within the chamber below 125 the upper receptacle and in spaced relation to said casing and having its upper end spaced from the lower end of the upper receptacle, means to cause air to circulate through and around said upper receptacle 130

and through the space between said receptacles, adjustable means to vary the space between said receptacles through which the air is permitted to circulate, and means for feeding the material to be separated to said upper receptacle.

6. In an air separator, the combination of a casing inclosing a chamber, an upper receptacle, means for supporting said receptacle within said chamber in spaced relation to said casing, a lower receptacle below the upper receptacle and having an upper open end spaced from the lower end of the upper

receptacle, spaced arms connecting said receptacle and secured thereto and supporting 15 the lower receptacle, means to cause air to circulate through and around said upper receptacle and through the space between said receptacles, adjustable means to vary the space between said receptacles through which 20 the air is permitted to circulate, and means for feeding the material to be separated to said upper receptacle.

In testimony whereof I affix my signature hereto.

GEORGE S. EMERICK.
